(57) **CLAIM**

The ornamental design for a microplate assembly, as shown and described.

DESCRIPTION

FIG. 1 is a top, front perspective view of a microplate assembly;

FIG. 2 is a front view of the microplate assembly;

FIG. 3 is a rear view of the microplate assembly;

FIG. 4 is a right side view of the microplate assembly;

FIG. 5 is a left side view of the microplate assembly;

FIG. 6 is a top view of the microplate assembly;

FIG. 7 is a bottom view of the microplate assembly;

FIG. 8 is a bottom, front perspective view of the microplate assembly;

FIG. 9 is a cross-sectional view of the microplate assembly taken along line 9-9 in FIG. 6 system; and,

FIG. 10 is a cross-sectional view of the microplate assembly taken along line 10-10 in FIG. 6 system.

The broken lines are included for the purpose of illustrating portions of the microplate assembly that form no part of the claimed design.
